UNITED STATES PATENT OFFICE.

EUCLID I. LA CHAPELLE, OF BROCKTON, MASSACHUSETTS.

MACHINE FOR RELASTING SHOES.

Application filed March 27, 1920. Serial No. 369,813.

To all whom it may concern:

Be it known that I, EUCLID I. LA CHAPELLE, a citizen of the United States, residing in Brockton, county of Plymouth, Commonwealth of Massachusetts, have invented certain new and useful Improvements in Machines for Relasting Shoes, of which the following is a specification, reference being had to the drawings accompanying the same and forming a part thereof.

This invention relates to machines for replacing shoes on lasts in a better, easier and more rapid manner than heretofore possible. This invention, however, has for a particular object the replacing of turn shoes on lasts.

In the manufacture of all kinds of shoes that require a relasting operation, it is now the universal practice to perform the relasting operation by hand; the last upon which the shoe is to be replaced being held in inverted position by a last pin while the shoe is being forced thereon but, in the case of turn shoes, the relasting operation is performed in the following manner:

After the shoe has been turned right side out, the relaster inserts to the inside bottom portion of the shoe, a filler, so-called, to which paste has been previously applied to hold the same to the sole and thereafter a shank-piece is inserted and nailed on to the sole. Then, the relaster dips the last into powdered chalk and inserts the forepart of the last partly into the forepart of the shoe and then he holds the forepart of the shoe and the corresponding forepart of the last within the shoe and he strikes, several times, the heel-end of the last quite forcibly against the end of a so-called relasting-post, which is usually padded with sole leather to overcome thereby, as much as possible the breaking of the last. Thus, the toe-end of the last is gradually forced toward the toe-end of the shoe and the shoe forepart relasting operation is completed when the toe-end of the shoe and the toe-end of the last finally meet.

Thereafter, the heel part of the shoe is relasted by setting the last on a last pin and by inserting a shoe heel relasting horn within the heel of the shoe and by moving the horn with the shoe over the heel part of the last.

Relasting any kind of shoes by hand is a laborious operation. In the case of turn shoes, it is a notable fact, that more time

is required at relasting than at any other turn shoemaking operation. The filler, which as already stated, is being held by paste to the shoe soie, is oftentimes displaced and moved into the extreme toe-end of the shoe under the influence of the frictional engagement of the shoe bottom and of the last bottom during the time of the shoe forepart relasting operation and this condition necessitates a last pulling operation and the relasting operation must again take place after the filler has been re-positioned within the shoe. The shoe lining is invariably wrinkled up, more or less, toward the toe under the influence of the frictional engagement of the last and of the lining during the time of the shoe forepart relasting operation and this wrinkled condition of the lining necessitates a smoothing out operation which requires much time and which is performed by means of a thin flexible strip of steel inserted between the last and the lining, after the entire shoe has been relasted, and which is manipulated to spread out the lining rearwardly. Moreover, lasts are often broken, or flattened and thereby shortened appreciably at the heel-end when the forepart is being relasted.

This invention contemplates overcoming the objections noted and contemplates facilitating and making the relasting operation, of all kinds of shoes, less laborious.

In the drawings:

Fig. 1 shows a side elevation of my novel relasting machine.

Fig. 2 is a plan view of said machine.

Fig. 3 is a section taken on line 3—3 of Fig. 1, showing the operating slide.

Fig. 4 shows the position of the members carried by said slide with relation to the last and in readiness to receive the shoe.

Fig. 5 shows the forepart of the shoe partly inserted on the last.

Fig. 6 shows the shoe engaging arms, as when held against the sole by the operator.

Figs. 7, 8 and 9 are details of the manner of relasting the heel part of the shoe.

Fig. 10 shows a sectional view of the clutch mechanism.

The base 1, has mounted thereon the upright, or post 2, having a last pin 2^a, at its upper end, which supports the last 3, and, at the rear of said post, the base supports the upright frame 4, which in turn supports the bar 5, on which the block 6, is slidably

mounted. Two arms, 7 and 7^a, are pivoted to said block at 8. The arms are curved inwardly at their shoe engaging ends; the curvature corresponding approximately to the curvature of the toe part of a shoe and secured to the inner faces of said curved portions of the arms are rubber pads, 7^b and 7^c. The arms, 7 and 7^a, are connected together by a bar 7^d, and the block 6, has mounted thereon a flat spring 9, which extends forwardly therefrom and which is positioned directly beneath the bar 7^d, thus holding the said arms in normal horizontal position, but yieldingly, to permit said arms to be moved downwardly when pressure is exerted upon them. The block 6, has also mounted thereon a bracket 10 through the end of which an adjustable screw 11, is mounted, and said screw is positioned directly over the bar 7^d, and forms a stop for limiting the upward movement of the arms 7 and 7^a. The block 6, has also mounted thereon a pair of thin arms, 12 and 12^a (preferably strips of spring steel) which extend forwardly in a plane slightly below and closer together than the arms 7 and 7^a, and said arms, 12 and 12^a, taper to a blunt point at their shoe engaging ends and terminate slightly in the rear of the ends of the arms 7 and 7^a. The arms, 7 and 7^a, have extensions 7^e, extending upwardly from the pivot 8, and said extensions are joined together by the bar 7^f, to the centre of which a cable connection 13, is attached and said cable passes around pulleys 14, 15, and 16 and through the winding drum 17, which is loosely mounted on a shaft 18, and the said drum forms the female part of a clutch member 19, said member being secured to the shaft 18, by a pin and slot connection, and is continuously driven by the gears 20, 21 and pulley 22. On the rear of the post 2, is secured a slide-way 23, on which is slidably mounted the block 24, and said block is connected by the link 25, to the disc 26, mounted on the shaft 27, which carries a gear 28, which meshes with the gear 21, and is continuously driven thereby. Secured to said block 24, is the heel relasting device.

In the operation of the machine, the operator pulls the block 6, forwardly until the ends of the arms 12 and 12^a are approximately opposite the toe-end portion of the last 3, and these arms being flexible may be forced toward the last and thus may be made to conform to the shape of the last and lie closely thereagainst while the shoe forepart is being placed on the last by the operator. The arms 7 and 7^a, are at this time opposite and slightly forward of the toe portion of the last, as shown in Fig. 4, but are spaced apart far enough so as not to interfere with the placing of the forepart of the shoe on the last by the operator, as shown in Fig. 5, after which the arms 7 and

7^a, are manually pressed inwardly until the rubber pads engage the edge of the sole at the toe portion, as shown in Fig. 6, and, while the arms are being held in this position, the operator presses the clutch-lever 29, which causes the drum 17, to be rotated so as to wind up the cable 13, for causing rearward pulling action on the arm 7^c, which swings the arms 7 and 7^a, slightly upward to cause thereby separation of the shoe bottom and of the last bottom by said arms.

As soon as the connecting bar 7^d, comes in contact with the stop-screw 11, the upward movement of the arms stops and the block 6, and both sets of arms, start then to move rearwardly; meanwhile the arms 7 and 7^a, pull the forepart of the shoe on the last and the arms 12 and 12^a, hold the lining in spread out condition and also overcome most of the friction of the last and lining. The arms 12 and 12^a, are also intended to spread out the lining preparatory to the start of the shoe forepart relasting operation. The shoe heel relasting horn 30, is now placed within the heel of the shoe, as shown in Fig. 7, and as the block 24, travels downwardly, the relasting horn is thereby pulled over the last with the shoe, as shown in Fig. 8, and the block 24, continues moving down until the relasting horn is pulled out of the shoe and then the shoe relasting operation is completed.

In relasting other kinds of shoes than turn shoes, such as, for example, McKay shoes, I preferably engage the shoe with the arms 7 and 7^a, below the edge of the sole and, to positively lift up the shoe bottom from the last bottom thereby, the top edges of said arms then engage the plane surface of the shoe sole-extension. The said arms may for this purpose be fixed lower, than now shown, on the block 6, or said arms may be shaped so that the surface of the shoe sole-extension may be thereby engaged uniformly from the ball-line to the toe portion of the shoe.

I, preferably, embody in my present novel relasting machine, although not absolutely necessary to this invention, strips of flexible steel 12 and 12^a, and these strips are substantially as shown and described in my previous United States patent, dated March 16, 1915 No. 1,132,479. But, I do not herein claim, of course, anything disclosed in said patent. Furthermore, the combination, as herein shown and described, of the post 2, the last pin 2^a, the block 24, the shoe heel relasting horn 30 and the connections, between the said block and the said horn, constitutes an old and well known combination and I do not claim anything in so far as this combination by itself is concerned.

The shoe heel relasting horn 30, may serve to simultaneously relast both, the heel part and the forepart of such shoes as McKay

shoes, after the shoe bottom and the last bottom have been separated, but good practice dictates that it is of the utmost importance in turn shoemaking, to firmly set the toe 5 part of the shoe upper, and intermediate parts to the toe of the last at the time of the shoe forepart relasting operation, as a proper preparation for the heel relasting operation, and I, therefore, preferably do so 10 in relasting turn shoes.

A very important feature, therefore, of my invention, and one which is novel per se, so far as I am aware, resides in the adaptation of the arms 7 and 7^a, for downward 15 movement to permit the operator to cause the shoe upper to be thereby engaged at the toe portion, independently of the shoe sole, for the completion of the shoe forepart relasting operation by firmly setting the shoe 20 upper, and intermediate parts, to the toe portion of the last by moving during this time the said arms rearwardly, by hand or by motive power, against the toe of the shoe and last. This shoe upper setting operation 25 is particularly beneficial when the tip, or the box-toe piece is heavy and by setting the shoe upper on the last, as herein proposed, the shoe upper is thus positively set to the last and this operation properly completes 30 the turn shoe forepart relasting operation.

A further very important and novel feature of this invention, and one which is novel per se, so far as I am aware, resides in the embodiment in relasting machines of 35 shoe bottom lifting means, whereby the shoe sole, and of course the remainder of the shoe bottom, may be separated from the last bottom to overcome thereby most of the friction at these portions between a last and a shoe 40 during the time of the shoe forepart relasting operation.

Additional novel features will be pointed out in the appended claims. I want it well understood that the present novel relasting 45 machine may be employed for relasting all kinds of shoes which require such an operation. The last used at relasting is usually of smaller size than the last upon which the shoe was lasted and the shoe, under this condition, fits somewhat loosely to the lines of 50 the last.

This present invention contemplates replacing in a shoe the same size last as was originally in the shoe and the novel feature 55 of separating the shoe bottom and the last bottom, as already herein noted, is of great importance in making this possible.

I want it well understood that I claim as 60 novel and as within the spirit of my invention and of this patent the embodiment, in any apparatus, device or thing adapted to the relasting of the foreparts of shoes, of the elements 7 and 7^a directed to that purpose as broadly recited in claims of this patent, whether or not actuating means be used

in conjunction therewith, as it is obvious that said arms 7 and 7^a, as shown in the herein illustrated machine, can be operated by hand to separate the shoe sole and the last bottom and that said arms can also be operated by hand to relast the shoe forepart. 70

I do not limit myself to the exact form of the machine herein shown and suffice it to say that I wish to be limited by the appended claims only. 75

Having thus described my invention, what I claim as new and desire to secure by Letters Patent of the United States is:

1. A shoe relasting machine, having, in combination, shoe forepart relasting means, 80 comprising shoe sole engaging means for lifting the shoe sole from the last bottom during the time of its shoe forepart relasting operation and a co-operating last holding pin. 85

2. A shoe relasting machine, having, in combination, the elements recited in claim 1 and a shoe heel relasting horn. 90

3. A shoe relasting machine, having, in combination, shoe forepart relasting means, 95 a shoe heel relasting horn, a single actuating means for said shoe forepart relasting means and for said shoe heel relasting horn and means whereby the operator may cause said shoe forepart relasting means to be actuated 100 by said single actuating means independently of the actuation of said shoe heel relasting horn. 105

4. A shoe relasting machine, having, in combination, the elements recited in claim 3 100 and a co-operating last holding pin. 110

5. A shoe relasting machine, having, in combination, a plurality of shoe relasting means and actuating means for actuating constantly some of said plurality of shoe 115 relasting means to expedite the relasting operation thereby. 120

6. A shoe relasting machine, having, in combination, a shoe heel relasting horn, shoe forepart relasting means, for separating the 120 shoe sole and the last bottom during the time of its shoe forepart relasting operation and a last holding pin. 125

7. A shoe relasting machine, having, in combination, the elements recited in claim 6 and a single power actuating means for 130 said shoe forepart relasting means and for said shoe heel relasting horn. 135

8. A shoe relasting machine, having, in combination, shoe forepart relasting means, 140 comprising means adapted to be placed between a shoe and a last and means for separating the shoe sole from the last bottom during the time of its shoe forepart relasting operation. 145

9. A shoe relasting machine, having, in combination, shoe forepart relasting means, comprising a plurality of elements and so arranged that the shoe sole and the last bottom will be separated by some of said plu- 150

rality of elements preparatory to the start of the shoe forepart relasting operation by said shoe forepart relasting means.

10. A shoe relasting machine, having, in combination, last holding means, shoe forepart relasting means and actuating means therefor, said shoe forepart relasting means being so arranged that the operator may control the duration of its relasting operation independently of said actuating means.

11. A shoe relasting machine, having, in combination, shoe forepart relasting means, adapted to engage the shoe sole and mounted for movements in a direction to cause the shoe sole to be thereby lifted from the last bottom and in another direction to cause the shoe forepart to be thereby relasted and co-operating last holding means.

12. A shoe relasting machine, having, in combination, the elements recited in claim 11 and a single actuating means for actuating said shoe forepart relasting means in both of said directions.

13. A shoe relasting machine, having, in combination, shoe forepart relasting means, for engaging a shoe at its outside portion and constructed and arranged to separate the shoe sole and the last bottom and co-operating last engaging means.

14. A shoe relasting machine, having, in combination, shoe forepart relasting means, constructed and arranged to separate the shoe sole and the last bottom during the time of its relasting operation and means for holding said shoe forepart relasting means yieldingly toward the shoe in the machine.

15. A shoe relasting machine, having, in combination, shoe forepart relasting means, comprising a shoe engaging element to engage the shoe at its outside portion, at one side thereof, and an additional shoe engaging element to engage the shoe at its outside portion, at the opposite side thereof, and arranged to separate the shoe sole and the last bottom, for the purpose described, and co-operating last engaging means.

16. A shoe relasting machine, having, in combination, movable shoe forepart relasting means, whereby the sole and the last bottom may be separated, and limiting means to limit the separating movement of said movable shoe forepart relasting means.

17. A shoe relasting machine, having, in combination, last holding means, shoe heel 55 relasting means, shoe forepart relasting means, whereby a shoe may be moved lengthwise of a last, and lining spreading means for smoothing out the shoe lining preparatory to the start of the lengthwise movement of the shoe relatively to the last by said shoe forepart relasting means.

18. A shoe relasting machine, having, in combination, shoe forepart relasting means, last holding means, shoe upper setting 65 means and actuating means for said shoe upper setting means, said shoe upper setting means being adapted to engage the shoe upper at its toe-end, and so arranged that the toe-end of the shoe upper may be thereby firmly set to the toe-end of the last and so arranged that its action upon the shoe upper under the influence of said actuating means may be terminated independently of said actuating means.

19. A shoe machine, consisting of last holding means, shoe upper setting means, adapted to contact with the toe-end of a shoe for performing the completion of the relasting operation of a shoe which has been 80 replaced on its last and actuating means therefor, said shoe upper setting means being so arranged that its action upon the toe-end of the shoe may be terminated independently of said last holding means and 85 of said actuating means.

20. A shoe machine, consisting of last holding means, and shoe lifting means adapted to engage the top plane surface of the extension of the sole of a shoe on a last, 90 for lifting thereby the shoe bottom from the last bottom, for the purposes described.

21. A shoe machine, consisting of the elements recited in claim 20, and actuating means for some of said elements.

22. A shoe machine, consisting of last holding means, and means, adapted to engage the plane surface of the shoe sole next to the shoe upper for separating thereby the shoe bottom and the last bottom during the time of the shoe forepart relasting operation.

In testimony whereof, I have signed my name to this specification.

EUCLID I. LA CHAPELLE.
